SEWING MACHINE

Karl Heil, Frankfort-on-the-Main, Germany, assignor to the firm Maschinenwerke zu Frankfort a. M. vorm. Kolb, Rieber & Co. G. m. b. H., Frankfort-on-the-Main, Germany

Application November 3, 1937, Serial No. 172,505
In Germany November 24, 1936

6 Claims. (Cl. 112—104)

The invention relates to a sewing machine with an oscillating head for the needle shank bearing for the production of groups of stitches and in particular for the sewing on of pom-poms and other decorations on house shoes and the like. An important object of the invention consists in the head carrying the upward and downward moving needle rod being displaceable transversely to the plane of oscillation for the purpose of producing a group of stitches defining a polygonal outline.

The accompanying drawings illustrate by way of example certain embodiments of the invention.

Figure 1 is a longitudinal section through a sewing machine made according to the invention;

Figure 2 is a view of this machine from the front seen in the direction of the arrow A of Figure 1;

Figure 3 is a plan of the machine;

Figures 4-6 show in front view, side view and plan the form of a revolving looper;

Figures 7-15 show this looper in seven different positions of rotation during the forming of the loops;

Figure 16 is a front view of a different and particularly advantageously designed looper;

Figure 17 is a section through this looper;

Figure 18 is a plan of this looper;

Figures 19-27 show this looper in the formation of the loop in seven different positions of rotation;

Figure 28 shows a separate device for automatically controlling the movement of the work pressure foot;

Figure 29 is a fragmentary view, partly broken away, of the looper drive shaft.

Figures 30 and 31 are side and end elevations, respectively, of one of the elements shown in Figure 29.

The main spindle 3 for the upward and downward movement of the needle and which extends at the front into the head 2 carrying the needle bar bearing at the back is coupled non-rotatably but movable axially, within a sleeve 4 carried in the arm housing 1 of the machine. The crank disc 5 which by a connecting rod 6 moves the needle bar 7 up and down, is fitted on the shaft 3 and the needle bar 7 carries the needle 8. The spindle 3 is slidably but non-rotatably connected to the sleeve 4 by the key 47 which extends radially from the shaft 3 and rides in a slot in the forward end of the sleeve 4 so as to key the shaft and sleeve together for rotation while permitting relative axial motion. On the head projection embracing the spindle 3 are

fixed the clamping pieces 9 and 13 of which the clamping piece 9 causes a movement axially of the shaft 3 to the needle bar head, whilst the clamping piece 13 serves for imparting an oscillating movement thereto. The clamping piece 9 is controlled by the roller 10 which runs in the circumferential groove 11 of the cam piece 12. This cam piece also has an end surface groove 11' in which runs the roller 14 carried on the clamping piece 13; as shown, the circumferential groove 11 effects a movement of the needle bar bearing in the direction of the main spindle 3 and the end surface groove 11' effects an oscillating movement of the needle bar bearing, the axial movement being of insufficient amount to remove the roller 14 from its groove 11' about said spindle 3.

The sleeve 4 is carried by means of ball bearings 15 in the housing 1. The friction pulley 19 is axially movable on the sleeve 4 but is prevented from rotating thereon by means of a key. There is furthermore fitted on the sleeve 4 loosely rotatable the gear 16 as also the wedge block 17a which is secured from rotation by the fork wedge 17 surrounding it. Between the block 17a and the friction disc 19 keyed to the sleeve 4 is the thrust ball bearing 18. The friction disk 19 cooperates in the usual way with the continuously rotating belt pulley 20, depressing the wedge 17 forcing the block 17a to the right as viewed in Figure 1, and forcing the disk 19 into driven engagement with the pulley 20, lifting the wedge 17 permitting the disk 19 to retract from the pulley. On the wedge 17 is provided a brake piece 21 for stopping the friction pulley 19 and an arresting roller 22 the use of which will be explained later.

In the housing 1 is furthermore carried a control shaft 23 on which are fitted the cam piece 12, a gear 24, a bevel gear 24a and a gear 25; these gears are fixed on the shaft 23. A further spindle 26 is journaled in a bearing 27 of the housing 1 and is prevented from axial displacement by a set ring as also by the bevel gear 28. The bevel gear 28 is firmly fitted on the spindle 26 and meshes with the bevel gear 24a. The front end of the spindle 26 is connected by two universal joints 29, 29' (and an extensible intermediate portion) with a spindle 30 which is journaled in a foot 36 of the downwardly extending arm 2' of the head 2 and carries at the front end forwardly of the bushing 32 the bevel gear 31. The latter meshes with the bevel gear 34 which is also carried in a part of the foot 36 which is the carrier body of the lower loop

forming mechanism, and is connected by the set screw 37 with the rotating looper 35. The looper axis is so arranged that it intersects the axial direction of the needle rod.

5 There is furthermore fitted on the carrier body 36 the needle plate 33. This needle plate suitably accompanying therefore the movements of the needle bar head is fitted close under the stationary work supporting table 49 which forms 10 the front end of a bracket arm 41 which can be adjusted in different fixed positions at the eyes 42, 43 of the housing 4 by means of eccentric pins 44, 45. The bracket arm forms at 38 the bearing for a double armed lever 39 which at 15 the front end (over the needle hole on the work table) carries an open funnel 40 widening out upwardly, as holder for the work, and the rear end of which is connected by a chain with a treadle (not shown). By means of a tension spring 50, the funnel 40 is kept continually pressing 20 down on the supporting table 49.

The operation of the sewing machine, assuming that this is to serve for sewing pom-poms on to house-shoes by means of four stitches to be placed in the corners of a square is as follows. The machine is at rest; only the belt pulley 20 runs idly. By actuating a treadle the lever 39 is drawn down at the rear end whereby the funnel 40 at the front end of the lever is 30 raised from the supporting table 49 and gives room for placing in position the house-shoe together with the pom-pom placed in the desired position. When the articles lie in the correct 35 position on the table 49, this treadle is released, whereupon the funnel 40 is spring pressed onto the articles and holds them firmly. The shape in funnel form of this part is particularly advantageous since it presses down the pom-pom threads only in the inner part, whilst the outer 40 part remains free and loose; the pom-poms thus retain a better appearance (see Fig. 7); in addition, the funnel forms an excellent finger protection from damage by pricking where the operator unnecessarily allows the hand on the 45 starting of the machine to rest on the workpiece table.

After the clamping of the work pieces, a second treadle is actuated which by means of the connecting rod 46 draws the wedge 17 downward, thus pressing the wedge block 17a against the friction disc 19 which is now coupled with the belt pulley 20 and can also immediately rotate since on the drawing down of the rod 46, the brake piece 21 is drawn downward and has 50 released the friction disc 19. The friction disc 19 and with it the sleeve 4, as also the shaft 3, will now be set in rotation; this rotation will continue on the release of the second treadle since on the rising of the connecting rod 46 the 55 arresting roller 22 fixed on it is no longer in the notch intended for it in the hub of the gear 16 (this gear has in the meantime further rotated) and consequently the connecting rod cannot reach its highest position, so that neither 60 the wedge 17 can effect a disengagement of the friction disc nor can the brake piece 21 reach the brake rim or flange running round the friction disc 19. The dropping of the roller 22 into the notch and thus the stopping of the machine 65 will only take place when the gear 16 has completed a full revolution. If now the gear ratio from the gear 16 to the gear 25 is chosen at 2:1 and from the gear 24 to the gear 24b at 4:1, it will be seen that with one rotation of the 70 gear 16 the shaft 23 carries out two revolutions,

and the spindle 3 eight revolutions. (The shaft 3 rotates through the key 47 with the sleeve 4 forming the hub of the gear 24b but the key permits axial displacement.)

The cam grooves 11 and 11' on the cam 12 5 are so arranged that with a shaft rotation of the spindle 23 (that is, with four rotations of the shaft 3) in consequence of the in and out and of the swinging movement of the needle bar bearing, the needle makes four double stitching strokes which are located in the corner points of a square. In making these stitches the needle bar axis takes four positions which are located on a wedge-like surface with the apex directed upwards. The cam grooves 11 and 11' 15 are preferably so chosen that the necessary forward and backward movement and the lateral displacement of the needle bar bearing take place in the pauses between the stitching strokes.

After carrying out the first four stitches, the 20 cycle is recommenced again in the same way, the needle on the repetition coming again into the old stitch holes whereby a raveling out of the seam (with chain stitch) is made difficult. After carrying out the eighth stitch, the sewing machine 25 stops in consequence of the roller 23 falling into its arresting notch. By actuating the first treadle, the funnel 42 can be raised and the sewn work be exchanged for work to be sewn. The operator has only to look after this replacement 30 of the work; holding it during the sewing process is unnecessary.

The connection of the four stitches takes place in the present example in chain stitch manner by the revolving looper 35 which is so constructed that it draws the loop formed at the time through the previously produced one. The shape of the looper is illustrated by Figures 4-6; the Figures 7-15 show the stitch formation procedure, it being clearly shown how the formed 40 loop travels from the front part of the looper to the back and then on the approach of the needle for the next loop is again moved forward in order at the right moment to pass under the needle so that the needle can pass through it. 45 To this end, the looper 35 has a special aperture 35' in its head.

Figures 16 to 18 show a looper of different design and the loop formation in various positions of rotation being shown in Figs. 19 to 27. 50 The looper according to Figs. 4 to 6 is not well suited in those cases where the article or the decoration are of non-uniform flexibility or contain hard parts embedded therein. In such cases, it may at times occur that the needle is deflected 55 and then does not pass into the opening 35', so that breakage of the needle may occur. In order to be able to advantageously employ the invention in such difficult cases, according to Figs. 16 to 18 the loop forming part of the looper 60 51 is made hollow so that the needle projecting beyond its axis never strikes against an obstacle even in the case of marked deflections. In Figure 17 the actual looper body is enclosed by a casing 52 of conical form fitted firmly thereto 65 but which is omitted in Figs. 16 and 18 for the sake of clarity.

The looper body merges at the rear into the pin 53 and has at the front the spiral shaped looper tooth 54 curved round the axis of the 70 looper and which from approximately its centre up to its tip is provided with a spreading piece 55 which serves as bearing wall for the one branch of the loop.

Figures 19-27 show the looper when forming 75

the stitch. In Figure 19 it is assumed that the sewing commences and that the needle 8 has for the first time penetrated the work and also the pom-pom to be sewn thereon, and is on the return from its lowest position. In Figure 20 the needle has risen a further amount; the tip of the looper tooth 54 penetrates into the gap between the needle 8 and the thread. The following figures represent the further positions of rotation 10 of the looper revolving clockwise. The formation of the loops and their taking by the looper tooth will be seen; in Figure 23 there is for the first time shown the opening out of the loop by the spreader 55. Figures 24-27 show the motion of the opened-out loop by the member 55 and Figures 26-27 show the penetration 15 of the needle into the opened-out loop for the start of the formation of the new loop within the one before. Figure 27 corresponds with respect to the position of rotation of the looper to Figure 20. During the further rotation of the looper the situations shown in Figures 20 to 27, inclusive, are repeated with the formation always 20 of a new loop within the loop formed during the previous revolution.

The means for practising the invention as described is capable of many modifications without departing from the inventive idea. Thus, for example, on varying the transmission ratios of the corresponding gear transmissions, 25 stitch groups may be easily formed with only three or with more than four stitches, and on the other hand instead of the two-fold placing of the separate stitch groups, a three-fold, four-fold, etc, or even just a single stitch group may be formed. The control movement of the needle bar bearing can be produced instead of by the grooves of a cam in any other known way. By varying the curves, the distance apart of the 30 stitches from each other can be increased or reduced; this is of importance with pom-poms since preferably the stitches are made so far from each other that the pom-pom knot is not penetrated, while on the other hand it is sewn on as close to this knot as possible in order not to press the pom-pom down more than can be helped.

A further perfection of the machine can consist in the funnel 40 serving to hold the work down not being actuated by a separate treadle but the lever 39 carrying the funnel 40 being connected by a spring rod with the wedge 17 so that by the drawing down of the connecting rod 46 at the same time and automatically, the funnel 40 is lowered onto the work, where it remains until the machine has carried out the prescribed number of the stitches. Fig. 28 shows such a construction; a lever 56 carrying the funnel 40 and being pivotable at 38 is connected 45 by a pivot 57 with the rod 58 carrying a sliding block 59 between helical springs 60, 61. The sliding block 59 is pivoted at 62 to the connecting rod 46 which actuates the wedge 17. Simultaneously with the disengagement of the sewing machine drive, the funnel 40 is raised and remains in this position until on the next engagement of the machine drive by drawing down the rod 46 it is forced down onto the fresh work inserted in the meantime. This modification 50 saves a treadle and has the advantage that the work can be placed on the machine during the stoppage thereof.

Figs. 29-31 show the extensible intermediate portion "29" (see Fig. 1) between the two universal joints 29, 29' clearly and to a larger scale.

The intermediate portion consists of two sleeves 63, 63' pivoted to the joints 29, 29' and having longitudinal slots 64, 64'. These slots embrace projections 65 of a hollow middle piece 66 and the sleeves 63, 63' are spaced each to the other 5 in such a way that the middle piece 66 is axially movable in them. The engagement of the projections 65 with the sides of the slots 64, 64' causes the shafts 26 and 30 to rotate simultaneously. The bore in the middle piece 66 is the same as in the sleeves 63, 63'; therefore an interior pin 67 may prevent the parts 63, 63', 66 from becoming disengaged while permitting lengthwise extension and contraction in accordance with the adjustment of the bracket arm 15 61 and the forward and rearward motions of the head.

The use of the machine is also not restricted to the field of sewing on pom-poms and other articles of decoration. For example the machine can be used also for the sewing on of perforated buttons. Also where only a temporary attachment of two or more articles is desired, the machine can be used with advantage, for example in dye works in order to attach together 20 articles of clothing, linen or pieces of fabric which appertain to each other and are to remain with certainty for the same length of time in the same dyeing agent.

I claim:

1. A sewing machine having a sewing arm, a sewing head, a reciprocable needle bar in said head, means for supporting said head for motion lengthwise of said arm and for oscillation about an axis lengthwise of said arm, and means actuatable during a sewing operation to impart said motions to said head to cause stitching to take place at points spaced in two relatively transverse directions.

2. A sewing machine having a sewing arm, a sewing head, a reciprocable needle bar in said head, a needle carried by said bar, means for supporting said head for motion lengthwise of said arm and for oscillation about an axis lengthwise of said arm, means cooperating with said needle to form stitches, means movable with said head for supporting said cooperating means, and means actuatable during a sewing operation to impart said motions to said head to cause stitching to take place at points spaced in two relative 40 transverse directions.

3. A sewing machine having a sewing arm, a sewing head, a reciprocable needle bar in said head, a needle carried by said bar, means for supporting said head for motion lengthwise of said arm and for oscillation about an axis lengthwise of said arm, means cooperating with said needle to form stitches, means movable with said head for supporting said cooperating means, driving means for said needle bar and cooperating means, and means driven by said driving means for imparting said lengthwise and oscillatory motions to said head.

4. A sewing machine having a sewing head, a needle bar reciprocable in said head, means supporting said head for rocking motion about an axis and for motion substantially parallel to said axis, means for reciprocating said bar, a work support beneath said needle bar, a needle carried by said bar, mechanism beneath said work support with which said needle cooperates to form stitches, means carried by said head for supporting said mechanism, means for actuating said mechanism, and means for moving said head alternately parallel to said axis and rocking 70 75

on said axis between successive complete reciprocations of said needle bar.

5. A sewing machine having a casing, a sewing head carried by said casing for oscillation about a pivot and for motion parallel to the axis of said pivot, a stationary work support carried by said casing, a looper positioned beneath said work support, a bracket carried by said sewing head and supporting said looper for motion with said head, a needle bar carried by said head and supporting a needle for cooperation with said looper, means in said casing for actuating said needle bar and for moving said head, and an extensible shaft from said actuating means to

15 said looper.

6. A sewing machine having a casing, a sewing

head carried by said casing for oscillation about a pivot and for motion parallel to the axis of said pivot, a stationary work support carried by said casing, a looper positioned beneath said work support, a bracket carried by said sewing head and supporting said looper for motion with said head, a needle bar carried by said head and supporting a needle for cooperation with said looper, means in said casing for actuating said needle bar and for moving said head, and a shaft 10 including a pair of universal joints and an extensible and contractible portion between said joints operatively connecting said looper and actuating means.

KARL HEIL. 15
